UNITED STATES PATENT OFFICE.

HENRY P. CLAUSEN, OF MOUNT VERNON, NEW YORK, ASSIGNOR, BY MESNE ASSIGNMENTS, TO WESTERN ELECTRIC COMPANY, INCORPORATED, A CORPORATION OF NEW YORK.

CALL-DISTRIBUTING TELEPHONE SYSTEM.

1,199,158.

Specification of Letters Patent. Patented Sept. 26, 1916.

Application filed February 9, 1915. Serial No. 7,015.

To all whom it may concern:

Be it known that I, HENRY P. CLAUSEN, a citizen of the United States, residing at Mount Vernon, in the county of Westchester and State of New York, have invented certain new and useful Improvements in Call-Distributing Telephone Systems, of which the following is a full, clear, concise, and exact description.

10 This invention relates to call distributing systems, and is particularly designed for systems of this kind in which only part of the lines which are heavy users are provided with call distributing apparatus which automatically extends a calling line to an operator's position at which there are no unanswered calls at the time.

15 The principal object of this invention is to avoid the use of relays and other apparatus individual to the trunks or outlets which extend to the operators' positions. In this system the trunk outlet is provided at the operator's position with a spring jack and an answering lamp which are individual thereto and a relay which is common to all the outlets entering the position.

20 In the drawings, Figure 1 represents the application of my invention to a three-wire system; Fig. 2 shows a modification of the invention in which the features thereof are applied to a two-wire system.

25 The switches shown in the drawings, one of which is provided for each subscriber's line may be of any suitable design, those shown diagrammatically in the drawings being substantially the same as shown and described in Patent No. 1,181,911, issued March 16, 1915. It is to be understood that the trunks which terminate at the contacts 30 of the switches shown extend to a plurality of operators' positions.

40 The apparatus and circuits herein shown are of such a simple character as to be readily understood from the following description of the operation.

45 When the subscriber associated with the line 1 removes his receiver from the hook, a circuit is completed from battery 2 through the left winding of relay 3, left armature of cutoff relay 4 over the line through the substation apparatus and back to the right armature and back contact of relay 4 and right winding of relay 3 to ground and relay 3 is energized. We will now assume that the 50 trunk upon which the switch rests enters an

operator's position at which an unanswered call exists. As will later appear, barring relay 11 will be energized and a circuit will be completed from grounded battery through interrupter 5, innermost contact of relay 3, 60 left normal contact of relay 6, stepping magnet 7, lower back contact of relay 8, conducting segment 9 of the switch, brush 10, test contact in engagement therewith to ground through the left armature of barring relay 65 11. Stepping magnet 7 is energized, attracting its armature, causing the pawl 12 to ride up over the next tooth of the ratchet wheel 13 which carries the switch brushes. When the interrupter 5 breaks this circuit, magnet 70 7 is deenergized and its armature and pawl 12 are retracted by means of the spring 14, thus causing the brushes to engage the contacts in the next trunk. If the brushes had rested upon a busy trunk, even though the 75 barring relay 11 had not been attracted, the result would have been the same, as relay 8 at the switch associated with the busy trunk would then be energized, as will presently appear. This would place ground potential 80 upon the segment 9 at said switch and through the test brush thereof to the test contact of the trunk and thence to the multiple of said contact engaged by the test brush of the hunting switch. The repeated 85 energization and deenergization of stepping magnet 7 will continue until the switch brushes rest upon the contacts of an idle trunk entering an operator's position at which there are no unanswered calls, in 90 which case no busy potential will be supplied to the test contact of the trunk.

95 When relay 3 was energized a circuit was completed through relay 6 as follows: grounded battery, interrupter 5, innermost armature of relay 3, left normal contact of relay 6, stepping magnet 7, lower back contact of relay 8, left winding of test relay 6, outermost armature of relay 3 to ground. During the hunting operation, however, 100 relay 6 was not energized over this circuit due to the short circuit of its winding through the test contact. This short circuit being now removed, relay 6 starts to pull up and circuits are completed for the 105 right winding of relay 6 as follows: from grounded battery through relay 11, answering lamp 14, switch contact, brush 15, conducting segment 16, contact 17, right winding of said relay and outermost armature 110

of relay 3 to ground. Battery is also supplied momentarily through interrupter 5, innermost armature of relay 3, contact 18, contact 19, contact 17, and thence to ground 5 as before. Relay 6, in pulling up opens the stepping circuit and closes through its innermost right armature a circuit by means of which relays 8 and 4 will become energized when the operator inserts the answering 10 plug 20 in jack 21. Relay 11 pulls up and through its left armature, places ground potential on the test contacts of all the trunks entering the operator's position at which the selected trunk terminates, thus 15 making all of said trunks test busy and barring all other calls from the position. The above traced circuit through relay 11 also serves to light the answering lamp 14 associated with the jack 21 of the selected trunk. 20 The operator observing lamp 14 glowing inserts the plug 20 in jack 21, completing a circuit from grounded battery at 22, through the supervisory lamp 23 and armature of supervisory relay 24 in parallel, sleeve contacts of the plug and jack, conductor 25, switch contact at which it terminates, the brush in engagement therewith, conducting segment 26, conductor 27 innermost armature of relay 6, windings of relays 8 and 4 25 in series to ground. Cutoff relay 4 is energized, opening the circuit of line relay 3 which falls off. Holding relay 8 is energized, completing the line circuit and also completing through both windings of relay 30 6, a circuit which extends from grounded battery through relay 11, switch contact, brush 15, conducting segment 16, contact 17, both windings of relay 6 to ground through the inner lower contact of relay 8. 35 Previous to the deenergization of relay 3 a branch of this circuit which short circuited the left winding of relay 6 extended from the right winding of this relay to ground at the outermost armature of relay 3. But as 40 relay 3 falls off at the time relay 8 pulls up, battery will now flow through the left winding in the circuit just traced. This causes a reversal of the polarity of the current through this winding, and as the left 45 winding is the larger, a reversal of the polarity of the electromagnet, thus causing the relay armatures to be kicked off. After the contacts of its armatures are opened, reenergization of relay 6 is impossible until 50 line relay 3 is again energized. When the innermost right armature of relay 6 is retracted, it opens the circuit for relays 4 and 8, but a parallel path had been closed through the uppermost armature and contact of relay 8, thus insuring that the line 55 relay 4 and the cut-in relay 8 will be maintained energized as long as the answering plug 20 is in jack 21. When relay 6 retracted its armatures, it opened the circuit 60 of relay 11 and answering lamp 14, causing 65

the lamp to be extinguished and relay 11 to be deenergized thus removing busy potential from the test contacts of the several trunks entering the operator's position and rendering the position accessible to other calls. 70

In this system it will be observed that the answering operator is in direct contact with the calling subscriber's line circuit and therefore message registers and other devices associated with the line circuit may be satisfactorily operated, also the usual reverting busy test will be operative. 75

Relays 6 and 8 may be made of the slow-release type if desired. If relay 8 is made slow-to-release, the operator may momentarily withdraw her connecting plug without causing the connection to be released, and if relay 6 is made slow-to-release, its armature will not be dropped off when a called subscriber operates his switch-hook 80 to flash the signal before the operator. 85

Fig. 2 discloses an application of my invention to a two-wire line circuit. As herein disclosed, the cut-in or holding relay 8 and the cut-off relay 4 are connected in parallel 90 to the lower talking strand when a connection is established and only four sets of brushes or wipers are required in the trunk-hunting switch; also the relay 8 should not be made slow-to-release. Except as above 95 noted, this system is substantially the same in arrangement and operation as the one disclosed in Fig. 1 and as the corresponding parts have been indicated by the same reference characters, it is thought the operation 100 of this modification will be readily understood from the foregoing description. 105

Although a plurality of batteries are shown on the drawings, these may be and in practice generally will be one and the same 110 source of current.

It is obvious that this system may be modified so as to differ widely in detail from that herein shown without departing from the salient features of the invention. Applicant therefore desires it understood that his invention is to be limited merely by the scope of the appended claims. 115

What is claimed is:

1. In a telephone system, a test relay, a high and a low resistance winding on said relay, means for energizing said relay by current through its high resistance winding, a holding circuit for said relay extending through its low resistance winding, and means for including said high resistance winding in said holding circuit, the windings being so arranged that the inclusion of said high resistance winding in series with the low resistance winding will cause the deenergization of said relay. 120

2. In a telephone system, a test relay, a high and a low resistance winding on said relay, means for energizing said relay by current through its high resistance winding, 125

- a holding circuit for said relay extended through a contact thereof and its low resistance winding, and means for including said high resistance winding with said low resistance winding in said holding circuit, the windings being so arranged that the inclusion of said high resistance winding in the holding circuit will cause the opening of said relay contact.
- 5 3. In a call distributing system, a subscriber's line, a switch, trunk lines, means for causing the movement of said switch to associate said line with an idle trunk upon initiation of a call on said line, a test relay for causing upon its energization said switch to stop on an idle trunk, a holding relay for maintaining said line in association with said trunk, an energizing circuit for said holding relay extending through front contacts of said test relay, and a deenergizing circuit for said test relay extending through front contacts of said holding relay.
- 10 4. In a call distributing system, a subscriber's line, a switch at which said line terminates, trunk lines terminating at said switch, means for causing the brushes of said switch to traverse the terminals of said trunk lines upon the initiation of a call on said line, a test relay, means for energizing said relay when the switch unites with an available trunk to stop said switch, a holding relay for maintaining said line associated with the selected trunk, an energizing circuit for said holding relay extending through front contacts of said test relay, and means for causing the deenergization of said test relay upon the energization of said holding relay.
- 15 5. In a call distributing system, a subscriber's line, a switch at which said line terminates, trunk lines terminating at said switch, means for causing the brushes of said switch to traverse the terminals of said trunk line upon the initiation of a call on said line, a test relay, means for energizing said relay when the switch unites with an available trunk to stop said switch, a holding relay for maintaining said line associated with the selected trunk, an energizing circuit for said holding relay extending through front contacts of said test relay, and means for causing the deenergization of said test relay on the energization of said holding relay, and a locking circuit for said holding relay extending through a front contact thereof and a contact of said switch.
- 20 6. In a telephone system, an exchange, a plurality of operators' positions at said exchange, subscribers' lines, switches at which said lines terminate, distributing trunks extending from contacts of said switches to different operators' positions, means actuated upon the initiation of a call on a line for causing a switch to unite said line with an idle trunk extending to an idle operator's
- position, a relay for applying busy potential to contacts of a group of trunks entering said position, a holding relay, means for energizing said group relay upon the selection of a trunk by said switch, and means for energizing said holding relay when the operator answers a call, the operation of said holding relay serving to effect the deenergization of said group relay.
- 25 7. In a telephone system, an exchange, a plurality of operators' positions at said exchange, subscribers' lines, switches at which said lines terminate, distributing trunks extending from contacts of said switches to different operators' positions, means actuated upon the initiation of a call on a line for causing a switch to unite said line with an idle trunk extending to an idle operator's position, a relay for applying busy potential to contacts of a group of trunks entering a position, a holding relay, means for energizing said group relay upon the selection of a trunk by said switch, means for energizing said holding relay when the operator answers a call, the operation of said holding relay serving to effect the deenergization of said group relay and also to place busy potential on the test contact of the selected trunk.
- 30 8. In a telephone exchange system, an exchange, a plurality of operators' positions at said exchange, subscribers' lines, switches at which said lines terminate, distributing trunks extending from contacts of said switches to different operators' positions, means actuated upon the initiation of a call on one of said lines for causing a switch to unite said line with an idle trunk extending to an idle operator's position, lamps associated with the terminals of said trunks at said positions, a group relay for placing busy potential on a plurality of the distributing trunks entering an operator's position, and an energizing circuit for said group relay and said lamp completed through a contact and brush of said switch when the switch unites with an available trunk.
- 35 9. In a telephone exchange system, an exchange, a plurality of operators' positions at said exchange, subscribers' lines, switches at which said lines terminate, distributing trunks extending from said switches to said operators' positions, means actuated upon the initiation of a call on one of said lines for causing a switch to unite said line with an idle trunk extending to an idle operator's position, a relay common to a group of trunks entering an operator's position, contacts of said relay through which busy potential is supplied to the test contacts of said trunks, a signal device associated with each trunk at the operator's position, and circuits whereby said group relay and the appropriate signal device will be included in

series in an energizing circuit completed through a contact of said switch when the calling line is united to an available trunk.

10. In a telephone exchange system, an exchange, a plurality of operators' positions at said exchange, subscribers' lines, switches at which said lines terminate, distributing trunks extending from said switches to said operators' positions, means actuated upon the initiation of a call on one of said lines for causing a switch to unite said line with an idle trunk extending to an idle operator's position, a relay common to a group of trunks entering an operator's position for placing busy potential on the test contacts thereof, a signal device associated with each trunk at the operator's position, and means whereby an energizing circuit is completed through a contact of said switch for said group relay and the appropriate signal device in series when a calling line is united with an available trunk.

11. In a telephone system, an exchange, a plurality of operators' positions at said exchange, subscribers' lines, switches at which said lines terminate, distributing trunks extending from said switches to said operators'

positions, means actuated upon the initiation of a call on one of said lines for causing its switch to unite said line with an idle trunk extending to an idle operator's position, a relay common to a group of trunks entering an operator's position for placing busy potential on the test contacts thereof, a signal device associated with each trunk at the operator's position, circuits whereby an energizing circuit is completed through a contact of said switch for said group relay and the appropriate signaling device when a calling line is united with an available trunk, a holding relay for maintaining the line in association with said trunk, and means actuated upon the energization of said holding relay for causing the deenergization of said group relay and the return to normal of said signaling device.

In witness whereof, I hereunto subscribe my name this 8th day of February A. D., 1915.

HENRY P. CLAUSEN.
